UNITED STATES PATENT OFFICE.

RICHARD OLIVER, OF BROOKLYN, NEW YORK.

EAR-RING SHIELD.

SPECIFICATION forming part of Letters Patent No. 249,202, dated November 8, 1881.

Application filed July 20, 1881. (No model.)

To all whom it may concern:

Be it known that I, RICHARD OLIVER, of the city of Brooklyn, county of Kings, and State of New York, have invented a new and useful 5 Improvement in Ear-Ring Shields, of which the following is a full, true, and exact description, reference being had to the accompanying drawings.

It has been found to be a matter of considerable utility to protect valuable stones when set in ear-rings from observation at times, and various devices in the nature of shields have been constructed for this purpose; but they have generally proved either very expensive, 15 very fragile, or too heavy for the comfort of the wearer. Gold shields and shields made of enameled metal have been most commonly used, and they are liable to the above objections. I have discovered that a shield properly constructed of hard rubber or celluloid is most appropriate for this purpose, on account of the great lightness and strength of the material, and also from the fact that joints between different portions of such material are almost in- 25 visible.

My invention will be clearly understood from the accompanying drawings, in which similar letters refer to similar parts.

Figure 1 represents a view of the ear-ring

within one half of the casing or shell; Figs. 30 2 and 3, views of the two halves of the shell, and Fig. 4 a view of the ear-ring closed.

C represents the ear-ring: A and B the two halves of the hemispherical inclosing-shield. These halves are provided with corresponding 35 openings, so that when they are closed together a passage is left for the support of the ear-ring.

The shells are made by turning the rubber or celluloid with a proper tool, and should be 40 made very thin. The lap-joints by which the hemispheres are fitted together should be carefully made, and when the shield is properly constructed the joint between the hemispheres will be practically invisible. 45

What I claim as my invention, and desire to secure by Letters Patent, is—

The improved ear-ring shield, which consists of two notched hemispherical portions provided with suitable lap-joints and composed of hard 50 rubber or celluloid, and adapted to include and conceal the jewel of an ear-ring, substantially as described.

RICHD. OLIVER.
